AUTOMOBILE WINDOW MECHANISM

Daniel L. Chandler, Somerville, Mass., assignor, by direct and mesne assignments, of twenty-two per cent to George W. Ewing, Peabody, Mass., twenty-two per cent to Eugene B. Fraser, Lynn, Mass., thirteen per cent to Edwin M. Bailey, Swampscott, Mass., thirty-two per cent to Fred H. Rowe, Gloucester, Mass., and eight per cent to William H. Davis, Lynn, Mass.

Application October 19, 1935, Serial No. 45,750

1 Claim. (Cl. 292—305)

My present invention relates to doors and more particularly to automobile doors which are provided with glass window panes that can be opened and closed at the will of the occupant 5 of the vehicle.

The elevating mechanism of the conventional type operates from the outside of the door frame adjacent the vehicle seat by means of a crank lever associated with gear mechanism there being no counterbalancing provision for the weight 10 of the window. The result is that it takes considerable more force to raise the window than to open it. Another inconvenience is present in that the crank lever projects from the door and 15 interferes with the lower limbs of the occupant of the vehicle in the case of a large stature person also the crank lever often catches in the clothing of the vehicle occupant when entering or leaving the vehicle.

In my present invention, I have obviated all 20 of the above objections and have produced an automotive vehicle window mechanism which has a lever located preferably in the window sill of the door and which operates in a horizontal plane to open and close the window. The sash of the window is counterbalanced such that it takes no more force to close the window than it does to open it. When opening or closing the window, the first application of force applied to the 25 lever unlocks the sash and as the force is continued in a horizontal plane the window is opened or closed as the case may be, the window becoming locked in place when the force is discontinued.

The principal object of my invention is an improved automobile window mechanism;

Another object is an automobile window mechanism which counterbalances the window weight;

Still another object is an automobile window mechanism which is provided with an operating lever located in the window sill and having an operating movement in a horizontal plane with respect to the perpendicular motion of the window sash which it operates;

And still another object is the combination of a sash locking member and sash elevating and depressing mechanism which elevates or depresses the window sash and locks said sash in 50 any position all in one operation in which the force is applied in a horizontal plane, and

Other objects and novel features comprising the operation and construction of my invention will appear as the description of the same 55 progresses.

In the drawings illustrating the preferred embodiment of my invention;

Fig. 1 is a fragmentary side elevation as viewed from the inside of an automobile door a portion of the frame of the door being broken out to 5 more clearly show the mechanism. The solid lines indicate the window sash in a lowermost position, the dot and dash lines indicating the sash and mechanism in a partially raised position;

Fig. 2 shows an inside elevation partially broken away of the window lever locking and operating mechanism being enlarged to full size proportions;

Fig. 3 is a vertical cross-section taken on the 15 line 3—3 indicated on Fig. 2;

Fig. 4 is a full size side elevation of the counterbalancing spring mechanism; and

Fig. 5 is a vertical cross-section taken on the 20 line 5—5 indicated on Fig. 4.

Referring more in detail to the drawings,

Fig. 1 which illustrates the inner side of the automobile door is provided with a panel 10. On the inner side of the panel 10 and adjacent the rear end I have provided a vertical strap or 25 hanger member 11 the lower end of which is bent over at 12 to inclose the counterbalancing spring 13 one end of which is anchored by means of a hook 14 to the bottom 15 of the strap 11, as shown at Fig. 4. The inner end of the spring 30 13 is anchored in a slot located in a stud 16 which is secured to a bell-crank lever 17. The lower arm of the bell-crank lever 17 is connected with the lower side of the window sash frame 18 by means of a link lever member 19. The upper arm of the bell-crank lever 17 is pivoted to a horizontal lever member 20 the front 35 end of which is provided with a vertical portion 20a upon which is mounted a slidable plate 21. The plate 21 is provided with three stud members 22 solidly fixed in said plate 21 and having a shouldered body portion 23 adapted to engage in vertically elongated slots 24 located in the plate 20a, the plate 21 and studs 22 being 40 held in place by the head of the studs on the back side of the plate 20a such that the plate and studs 21 and 22 respectively may slide in a vertical manner upon each other. Solidly attached to the plate 21 at its top is a gear segment member 25 the teeth of which are adapted to engage in a rack 26 located on the bottom 45 of a slide-way member 27 which is horizontally attached to the inner side of the door panel 10. The plate 20a which is a part of the lever member 20 is supported in the slide-way 27 by

50 55

means of a shouldered stud 28 which is solidly secured to the plate 20a at its rear portion which is provided with a roller or shoulder 29 which is adapted to slide on the slide-way edges 27a. 5 A spacer plate 30 is securely attached to the plate 20a and the front face of said spacer 30 engages the back surface of the slide-way 27 aligning said slide-way up with the segment member 25 the teeth of which engage in the rack provided on the bottom of said slide-way 27, the slide-way 27 being in combination with the rack 26.

An opening 31 is provided in the plate 21 the top of said opening being provided with an outstanding bracket member 32 formed from a portion of the plate 21 and extending out beyond the upper portion of the opening 31 and further adapted to receive a compression spring 33 the lower end of which is anchored on a similar projecting bracket member formed from the plate 20a and projecting outwardly through the opening 31 in the plate 21, as shown in Fig. 3. A pin 35 is located in the bracket 34 for the purpose of maintaining the compression spring 33 in proper alignment. The spring 33 normally maintains the plate 21 in an upper position on the plate 20a and thereby keeping the segment teeth in engagement in the rack 26.

When the segment teeth of the member 25 are 30 engaged with the rack 26 no horizontal movement of the lever 20 is possible thereby making it impossible to open or close the window sash.

For the purpose of unlocking the segment 25 with the rack 26 and at the same time providing 35 a pull lever to operate the bell-crank lever 17, I have provided a hand lever 36 which is pivoted at 37 to the plate 20a. The lower portion of the hand lever 36 is provided with shoulders 38 oppositely opposed to each other and adapted to 40 engage over the flattened head portion of the upper studs 22 anchored in the sliding plate 21 which carries the segment 25. A guide stud 39 is located in the upper portion of the hand lever, the shouldered portion 40 being adapted to engage 45 in the radial slot 41 located in the upper portion of the plate 20a.

When the hand lever 36 is pulled forward or backward the first application of force pivots the lever 36 on the pivot 37 and the shoulder 38 50 depresses the stud 22 causing the plate 21 to slide downward disengaging the segment 25 from the rack 27 and by a continuation of the force applied in the horizontal plane the lever 20 is

slid forward or backward, as the case may be, actuating the bell-crank lever and raising the window or lowering it. The counterbalance spring 13 maintains the weight of the sash in a counterbalanced state such that very little force 5 is necessary.

When the lever 36 is released the compression spring 33 returns the plate 21 and segment 25 causing the segment teeth to engage in the rack 26 thereby locking the sash in any position desired. 10

Having thus described my invention what I claim as new is:

An improved sliding lock for window elevating mechanism comprising in combination, a plate 15 rigidly connected with said window elevating mechanism, said plate having a plurality of elongated slots, said slots extending through the said plate and being adapted to receive shouldered studs rigidly mounted in a second plate slidably mounted on one side of said first plate, an opening 20 in said sliding plate being adapted to receive therethrough a right-angle bracket attached to said first plate, a second bracket attached to said sliding plate adjacent one end of the said opening, a compression spring located between the opposed sides of the two said brackets for the purpose of maintaining the said sliding plate in an elevated position on said first plate, a depressed cam surface formed on the top edge of 30 said sliding plate, a hand lever pivoted to said first plate, a cam stud solidly attached to said hand lever, a radial slot located in the upper portion of said first plate and being adapted to receive the body portion of said cam stud, the 35 head of said cam stud being adapted to engage the said cam surface on the said sliding plate, a tubular horizontal slide-way having one side open and teeth formed on its lower edge, a stud journaled through said sliding plate and solidly 40 attached to said first plate, said journaled stud being provided with a shoulder engaged with the edges of the open side of said slide-way and an enlarged flattened head adapted to slide within said tubular slide-way, a rack engaging member 45 solidly attached to said sliding plate below the lower toothed edge of said slide-way, said engaging member having radially disposed teeth on its upper edge and being adapted to engage with the toothed openings in said lower edge of said 50 slide-way.

DANIEL L. CHANDLER.
